UNITED STATES PATENT OFFICE

THOMAS CLARENCE HEISEY, OF NEWARK, OHIO, ASSIGNOR TO A. H. HEISEY AND COMPANY, OF NEWARK, OHIO, A PARTNERSHIP

DESIGN FOR A FLOWER BOWL OR ARTICLE OF SIMILAR NATURE

Application filed May 1, 1929. Serial No. 31,067. Term of patent 14 years.

To all whom it may concern:

Be it known that I, THOMAS CLARENCE HEISEY, a citizen of the United States, residing at Newark, in the county of Licking and State of Ohio, have invented a new, original, and ornamental Design for a Flower Bowl or Article of Similar Nature, of which the following is the specification, reference being had to the accompanying drawings, forming a part hereof.

I claim:

The ornamental design for a flower bowl or article of similar nature, as shown.

T. CLARENCE HEISEY.
